UNITED STATES PATENT OFFICE.

JOHN W. DORSEY, OF WINNIPEG, MANITOBA, CANADA.

ELECTRIC HEATING SYSTEM.

Application filed September 18, 1920. Serial No. 411,103.

To all whom it may concern:

Be it known that I, JOHN W. DORSEY, a citizen of the United States, residing at Winnipeg, in the Province of Manitoba and 5 Dominion of Canada, have invented certain new and useful Improvements in Electric Heating Systems, of which the following is a specification.

This invention relates to an electric heating system for uniformly heating the human body.

The system is adapted for use indoors or out of doors and may function at the will of the individual, whether he be walking, 15 standing, or sitting.

The system provides for a plurality of stationary electric conductors connected to a central power source, and adapted to co-operate with contacts carried by persons 20 who walk or stand on such conductors and who wear the heating garment forming a part of the system.

Details of the invention provide for a garment adapted to snugly fit the human body and constructed with a flexible metallic weave, constituting a resistor heating body, and suitably insulated by layers of cloth on the inner and outer surfaces. This garment is connected to contacts carried on 25 the shoes of the wearer, and these contacts are arranged to co-operate with a series of conductors, usually placed on the foot and alternate members of which are connected to a source of energy in such a manner as to 30 complete a circuit from one stationary conductor through the heating garment and back to the next adjacent stationary conductor.

The advantages of the system are obvious. 40 The body may be uniformly heated regardless of the extremes of atmospheric temperature or weather conditions, and such uniformity is not possibly provided by any other manner of dress or heating system. 45 The system is equally well adapted for use in any location, whether in homes, factories, railway stations, or on side-walks. By using the system in buildings, it is at once unnecessary to maintain the inside temperature of the building as high as would be 50 necessary if the system were not installed, and accordingly the fuel costs are corre-

spondingly lowered. For use in the open, the stationary conductors may be located as desired, whether on the side walk, or in 55 public waiting places, such as street car transfer stations and railway station platforms. Prolonged exposure to cold caused by delay in train schedules may thus be avoided.

Another advantage resides in the fact that electric power may be purchased relatively cheaply during the day light hours, and this would make the use of the system in business places relatively inexpensive.

The system has one particular advantage 60 which resides in the fact that it is not necessary to alter buildings or other constructions in order to complete an installation. For instance, in a home, carpets or floor 70 coverings having conductors incorporated may be used and the occupants of the house may connect the carpet conductors to a suitable source of power, and by wearing the garment which is adapted to co-operate 75 with the carpet contacts, they may derive heat from the ordinary electric light circuit. Similarly, stationary metallic contacts, insulated from each other, may be located in factories, or in public places where persons 80 attending to their daily occupations may place the conductors carried by them in contact with the fixed conductors forming the stationary part of this system. One of the 85 peculiar advantages of the system is that it may be used without extra effort or thought on the part of the individual. The ordinary walking movements, standing and sitting positions, may place the connections from the heating garment in circuit with the stationary conductors. The use of the system 90 may, therefore, be readily adapted and introduced.

Other details and features of the invention will be set forth and claimed in the following specification and claims, and illustrated in the accompanying drawings, in 95 which—

Fig. 1 is a diagrammatic view showing in plan the arrangement of stationary conductors suitable for side-walks or hallways, and other floor surfaces.

Fig. 2 is a diagrammatic view showing in plan a similar arrangement to that shown in

Fig. 1, but having connections providing for a three wire system coupled to a suitable transformer.

Fig. 3 is a diagrammatic view showing in 5 plan an arrangement of the stationary conductors having intermediate insulating blocks of the same size as the conductors, this arrangement providing parallel rows of insulation blocks and positively and negatively connected conductor blocks.

Fig. 4 shows a type of floor covering suitable for use in houses and having concentric circles of electric conductive material incorporated therein and insulated from each 15 other, adjacent circles being connected to opposite sides of a source of power.

Fig. 5 is a view of a similar floor covering as that shown in Fig. 4, but providing a rectangular design for the conductor portions of the floor covering.

Fig. 6 is a view showing diagrammatically the arrangement of conductors illustrated in Fig. 1, but adapted to use on stairway constructions.

Fig. 7 illustrates the figure of a person 25 wearing the heating garment which forms a part of the system, and standing on adjacent plates or conductors of the floor portion of the system. The right side of the figure 30 shows the outer covering of the garment, and the left side shows the outer portion removed and illustrates the parallel arrangement of metallic material secured to the inner insulating cloth surface.

Fig. 8 is a diagrammatic view illustrating 35 the manner in which the circuit extends from the lower end of one leg of the garment, upwardly and to the extremity of one arm, across to the end of the opposite arm, 40 and downwardly to the lower end of the opposite leg.

Fig. 9 is a sectional view illustrating the 45 connection from the lower leg portion of the garment to the shoe, and the mounting of the contact plate in the sole of the shoe.

Fig. 10 is an enlarged view illustrating the construction of one form of weave of the resistor heating element which may be used.

Referring in detail to the drawings, Fig. 1 50 shows a series of metallic conductors illustrated as elongated rectangular plates, which may be used on side-walks. 1 indicates a positively connected conductor plate and the next adjacent plate 2 is connected to 55 the negative of a source of electrical energy. 3 indicates insulation space between the adjacent blocks. Wires, leading from a source of power, are indicated by 4 and 5, leading respectively to the positive and negative 60 plates. In operation the person wearing the heating garment, which forms a part of this system, steps from positive to negative conductor in the ordinary walking gait. At such time as both feet are on the ground, an 65 electric circuit is completed from positive to

negative for each successive step, the circuit being completed through the connections extending from the shoes of the wearer upward through one leg of the garment and finally down the other leg of the garment and 70 through the opposite shoe to the conductor plate. A resistor element 6 is provided to guard against undue heating of the garment and to cut off unusually heavy currents.

In Fig. 2 is an arrangement for using a 75 three-wire system connected to the secondary S of a transformer having a primary winding P. This arrangement includes positive conductors 1, negative conductors 2, the usual insulation 3 between the plates, 80 and a series of neutral conductors 7 suitably arranged for a three-wire system. Wires 8, 9 and 10 extend from the secondary S to the positive, neutral, and negative conductors, respectively. A blank and unconnected plate is illustrated at 1^a. In this arrangement also as well as in other forms suitable fuses should be provided as indicated at 6^a.

In Fig. 3 there is illustrated an optional 85 arrangement of stationary conductors in which the positive and negative conductors are separated by blocks of insulation material of the same size. The shape of the blocks is preferably square and where the 90 system is to be used in a side-walk, or where the travel is along a given line, it is desirable to place the blocks at an angle of 45° to the line of travel, as illustrated in Fig. 3. In this way, it is possible to step continuously on insulation material or to step alternately on positive or negative conductor members, which are arranged in parallel 95 rows at either side of the insulation material.

In order to differentiate readily between 100 insulation material and to readily discern a difference between positive and negative conductors, it is desirable to provide definite colors, such as black, red and blue to indicate the negative, positive and insulation 105 material, respectively. Where it is not desirable to use colors, any simple arrangement or manner of indication will prove 110 serviceable. The use of colors or other means of distinguishing conductors is not absolutely necessary, because by standing on one plate, there will be no electric circuit completed and, therefore, there could be no heat generated in the garment.

The conductors which have been described 115 as being stationary may be formed of any suitable material. For instance, they may be shown as solid metal plates, as indicated in Fig. 1, or there may be a series of metallic plates standing on edge and embedded in pavement surface, such plates being connected at their ends to the continuous frame of the contact member, as indicated by 1^b in Fig. 2.

The constructions shown in Figs. 4 and 120

5 represent floor covering constructions, such as carpets, in which there is a series of bands of conductor material incorporated into the body of the carpet. Alternate 10 bands of this material are separated by insulation of the carpet and the positive and negative bands are coupled up with a source of electric power by means of the wires 4 and 5 in a manner similar to the arrangement shown in Fig. 1. By the use of such floor coverings, it is possible to provide for the heating of the persons in a house and dispensing with much of the ordinary furnace heat. A person walking, standing, or 15 sitting in a room having such a floor covering, by placing a foot on adjoining bands of conductor material, may complete the circuit through the garment which is being worn by the individual.

20 Fig. 6 shows the connections for a stairway, which provides that the adjacent steps have conductors of positive and negative connection.

Referring in detail to the construction of 25 the heating garment which is designed to co-operate with the stationary conductors of the system, Fig. 7 shows a full-length view of such a garment. 11 is the heavy outer covering which is preferably made of 30 woolen material and adapted to retain the heat generated. 12 indicates the inner surface material which is adapted to rest on the underwear of the person wearing the garment. Located between the two layers 35 11 and 12 is an intermediate resistor body, preferably formed of woven metallic mesh arranged in strips extending lengthwise of the arms and legs and body portion of the garment. A suitable arrangement is shown 40 in Fig. 7 where the metallic strips 13 are placed close together, but spaced to provide for elasticity in the garment. The strips 13 are arranged in continuous form, so that the electric circuit is adapted to extend up 45 one leg of the garment, down one arm, across and down the other arm, and then finally down the other leg. The invention includes the use of a connection extending from the lower leg portion through shoes 50 14 and to a contact plate 15 secured to, or embedded in the sole 16 of the shoe. An electric wire connects the plate 15 by extending along the sole of the shoe, as indicated at 17. The wire 17 extends up at the 55 rear of the shoe and is preferably covered by a supplemental piece of leather. The upper end of the wire 17 is terminated in a contact button 18 over which a snap fastener 19 is adapted to fit. Extending upwardly from the snap fastener 19 is a wire or tape 20 having a second snap fastener 21 adapted to be secured to a contact button 22, which in turn is secured to the metallic material 13 of the heating garment.

in that portion immediately above the shoe or stocking. The length of the member 20, and the point of attachment of the contact button 22 is not material, but depends on the convenience and personal desire of the wearer.

70 Fig. 10 shows an enlarged form of the mesh of the metallic material 13. This material may be woven as indicated or may be manufactured by the interwinding of metallic threads in the form of tape, the metallic threads extending in and out of the tape and thus forming a very durable material, but less elastic than that illustrated in Fig. 10.

75 The invention includes the use of the heating garment with stationary contacts at such points as may be desirable so that the electrical circuit may be completed readily and during the ordinary movements of the individual wearing the garment. The use 80 of this system requires ease with which the contact is made and the circuit completed. For instance, the circuit may be completed by having contacts on each foot, or may be furnished by contact from one foot and a 85 cane carried in the hand of the wearer of the suit, in which case a conductor must extend the length of the cane and be connected to the garment by a fastener supplied at the end of the garment sleeve.

90 The size of the stationary conductors is preferably about twenty-four inches in width, substantially the same as a normal walking step, and the insulation between adjacent conductors is illustrated as about 95 three inches. These figures apply to the 100 diagrammatic representations in Figs. 1, 2, and 3, equally, although the conductors and other blocks in Fig. 3 are shown in reduced scale.

105 The mounting of the contact member 15 on the shoe may be modified as desired, and if preferable, may be applied to the heel, or to the toe and heel, so as to insure completion of the electrical circuit without the necessity of modifying the natural walking gait of the wearer of the garment.

110 What I claim is:

115 1. An electric heating system comprising a plurality of stationary contacts arranged in pairs of opposite polarity for connection with a source of electrical energy, a heating element for the human body, and contacts connected with said heating element and each adapted to be moved alternately into 120 and out of contact with one of said pairs of opposite polarity of said stationary contacts.

125 2. An electric heating system comprising a plurality of stationary conductors arranged in insulated relation to each other and at the floor or ground surface and adapted to be trod upon, and a heating element for the human body having conduc-

- 4
- tors adapted to contact with said stationary conductors.
3. An electric heating system comprising a plurality of stationary conductors in insulated relation to each other and adapted to be trod upon, and a heating element for the human body having conductors adapted to contact with said stationary conductors.
- 10 4. An electric heating system comprising a plurality of stationary conductors in insulated relation to each other and adapted to be trod upon, and a heating element for the human body, and connections extending from said heating element and terminating in contacts on the shoes of the wearer of said heating element, said contacts being adapted to engage said stationary conductors and supply electric current to said heating element.
- 15 5. An electric heating system comprising a plurality of stationary conductors in insulated relation to each other and adapted to be trod upon, a heating element for the human body comprising a substantially full length garment adapted to closely embrace the body to retain heat, and connections extending from said heating element and terminating in contacts on the shoes of the wearer of said heating element, said contacts being adapted to engage said stationary conductors and supply electric current to said heating element.
- 20 6. In an electric heating system, a stationary conductor located at the level of the floor or ground and adapted to be trod upon and to transmit electrical energy to heating apparatus carried by persons so stepping on said conductor.
- 25 7. In an electric heating system, a series of stationary electrical conductors arranged in insulated relation to each other and located at the floor or ground level and adapted to be trod upon.
- 30 8. In an electric heating system, a series of stationary electrical conductors arranged in insulated relation to each other and located at the floor or ground level and adapted to be trod upon, alternate members of said series being connected to the opposite poles of a source of electrical energy.
- 35 9. In an electric heating system, a series of stationary electrical conductors arranged in insulated relation to each other and located at the floor or ground level and adapted to be trod upon, alternate members of said series being connected to the opposite poles of a source of electrical energy, a heating element for the human body, and connections extending from said heating element and terminating in contacts adapted to engage alternate stationary conductors and receive electric current for said heating element.
- 40 10. In an electric heating system, a heating element for the human body, and connections extending from said heating element and terminating in contacts on the lower faces of the soles of the shoes of the wearer of said heating element, each of said contacts being adapted to engage electric conductors arranged in a plurality of pairs of opposite polarity and connected to a source of electric energy.
- 45 11. In an electric heating system, a heating element for the human body, and connections extending from said heating element and terminating in contacts on the lower faces of the soles of the wearer of said heating element, each of said contacts being adapted to engage electric conductors arranged in a plurality of pairs of opposite polarity, located at the ground level and connected to a source of electric energy.
- 50 12. In an electric heating system, a close fitting heating garment comprising outer layers of insulating material and an intermediate layer of electrically conductive material constituting a heating element, and connections extending from said garment and terminating in contacts adapted to engage contacts connected to a source of electric energy and located in the floor or pavement and adapted to be trod upon to complete the electrical circuit.
- 55 13. An electric heating system comprising a plurality of stationary conductors for connection with a source of electrical energy, connections extending from said conductors and adapted to be secured to a suitable source of electrical energy, a resistance element in circuit with at least one of said connections, a heating element for the human body, and contacts connected with said heating element and adapted to be moved alternately into and out of contact with said stationary contacts.
- 60 14. In an electric heating system, a series of stationary electrical conductors arranged in insulated relation to each other and located at the floor or ground level and adapted to be trod upon, alternate members of said series being connected to the opposite poles of a source of electrical energy, a resistance element located between said conductors and the source of power, a heating element for the human body, and connections extending from said heating element and terminating in contacts adapted to engage alternate stationary conductors and receive electric current for said heating element.
- 65 15. In testimony whereof I affix my signature.
JOHN W. DORSEY.
